UNITED STATES PATENT OFFICE.

CORNELIUS D. EHRET, OF PHILADELPHIA, PENNSYLVANIA.

METHOD OF AND APPARATUS FOR CONTROLLING ELECTRICAL ENERGY.

1,318,855.

Specification of Letters Patent.

Patented Oct. 14, 1919.

Application filed November 15, 1918. Serial No. 262,639.

To all whom it may concern:

Be it known that I, CORNELIUS D. EHRET, a citizen of the United States, residing in the city and county of Philadelphia, State 5 of Pennsylvania, have invented a new and useful Method of and Apparatus for Controlling Electrical Energy, of which the following is a specification.

My invention relates to a method of and 10 apparatus for controlling electrical energy, particularly for purposes of signaling, telephony, or telegraphy, either where the energy is transmitted from one point to another in radiant form, or when transmitted over a wire or other circuit.

My invention resides in a method of and 15 apparatus for controlling the production, amplification, or both production and amplification of electrical energy by thermionic or electronic action occurring in connection with an audion, dynatron, triode, vapor electric apparatus, and the like.

In accordance with my invention the electric energy controlled, rectified, amplified, 20 produced or otherwise acted upon by or in association with a thermionic or electronic device is controlled by changing or varying both the emission of electrons from a hot 25 cathode and the flow of electrons. This is effected by controlling the temperature of a part or less than the whole of the hot cathode and the potential of a grid, screen or similar electrode; and in the case of a 30 dynatron controlling the potential of one or more grids while controlling the temperature of the hot cathode, and more particularly of a part or less than the entire 35 hot cathode.

My invention resides in the method and 40 apparatus of the character hereinafter described and claimed.

This application is in part a division 45 from my application Ser. No. 209,445, filed December 29, 1917, and patented May 6, 1919, No. 1,303,184.

For an illustration of some of the various forms of apparatus embodying my invention and suitable for carrying out my method, reference is to be had to the accompanying drawing, in which:

Figure 1 is a diagrammatic view of a thermionic or electronic device in which the cathode is comprised of a plurality of parts, the temperature of one of which is con-

trolled simultaneously with control of potential of the grid.

Fig. 1^a is a fragmentary view illustrating a modification.

Figs. 2 and 3 are diagrammatic views of modifications.

Fig. 4 is a diagrammatic view of a thermionic or electronic device of the dynatron type embodying my invention.

Fig. 4^a is a fragmentary view illustrating a modification.

Referring to Fig. 1, A represents an audion, triode or other similar electronic or thermionic device. In the example illustrated, there are disposed within the evacuated bulb or vessel a the cathodes f and f¹, 70 in this case incandescent filaments of tungsten, carbon or other suitable material, the grid g and the wing, plate or anode w. Between one terminal of the filaments f and f¹ and the plate or wing w are connected any 75 source of current B of suitable electro-motive-force, and the primary p of a transformer or repeating coil whose secondary s delivers energy to any circuit, such as a circuit comprising a wire or wires extending 80 between the transmitting and receiving stations, and the antenna or other radiating element or structure of a wireless or radio communication system.

One terminal of the filaments f and f¹ 85 connects through the secondary s¹ of a transformer or repeating coil whose primary is p¹ to the electrode, grid or screen g. In this grid circuit may be connected a device b, which may be a condenser, as indicated in Fig. 1^a, or a source of electro-motive-force, such as a battery as indicated in Fig. 1; when a battery is employed, preferably its negative terminal is connected to the grid g and its electro-motive-force is 90 such as to maintain the grid suitably negative with respect to the cathodes f and f¹. In shunt to the transformer secondary s¹ may be connected also a source S of fluctuating or alternating current, and in the 100 case of telephony a source of fluctuating or alternating current whose frequency is above the limits of audibility.

For rendering the cathode f incandescent there is provided a source of current, as the 105 battery k, the strength of whose current through the filament f may be adjusted by the variable resistance r² for giving to the

cathode f a suitable normal temperature. The second filament f^1 is connected in circuit with the variable resistance r , the transformer primary p^1 , the signaling instrument m of any suitable character, as for example, a telephone transmitter or microphone m , and the battery c .

The cathode structure in this arrangement comprises the two filaments f and f^1 , f operating normally at such temperature as determined by the adjustment of resistance r^3 , while the cathode part f^1 is varied in temperature by variation of the current therethrough, whose normal value is determined by adjustment of resistance r , but which varies in temperature in accordance with the signal to be sent, or in the case illustrated, in accordance with sound waves, such as those of the voice, by the microphone m . Simultaneously the potential of the grid g is varied in accordance with sound waves by the same microphone m .

As a result the electron stream from the cathode structure to the plate or anode w varies in quantity for two reasons, one, the variation of temperature of the cathode f^1 , and, secondly, because of variation of the potential of the electrode or grid g . The result is a variation of current in the circuit of the primary p in accordance with speech with resultant variation of current in the secondary s in accordance with speech.

If the high frequency source S is employed, there will appear in the primary p and secondary s high frequency oscillations, whose amplitude is varied in accordance with the signal; and where the signaling instrument is the microphone m and the frequency of the current from source S is above audibility, the inaudibly high frequency current in primary p and secondary s is varied in accordance with speech both by the variations in temperature of the cathode f^1 and the grid g . For purposes of telephony, or other cases where the grid is influenced at high frequency, the cathode f^1 must be sufficiently fine or small to quickly or accurately respond to speech waves or other high frequency modulations.

In Fig. 2 is shown an audion or similar amplifier with a double filament arrangement similar to that shown in Fig. 1. In this case the filament f is in circuit with the battery k and the adjustable resistance r^3 , and the filament f^1 is in series with the same battery and resistance with the second microphone m^1 in series with them. The microphone m and the battery c are connected in series only with the primary p^1 . The two microphones are disposed close to each other, so that the speech or sound waves impinge on them simultaneously. In this case the microphone m varies only the potential of the grid g , while the microphone m^1 varies the temperature of the filament f^1 .

If a high frequency source S is employed in the grid circuit there will appear in the secondary s high frequency energy whose amplitude varies in accordance with the signal or sound waves.

In Fig. 3 is shown an audion or similar amplifier involving two filaments, of which f is in circuit with the battery k and the adjustable resistance r^3 ; the second filament f^1 is in circuit with the battery k , adjustable resistance r^3 and the secondary s^4 of a transformer or repeating coil whose primary is p^4 connected in series with the primary p^1 , battery c and microphone m . Here again the microphone simultaneously controls the potential of the grid g , and the temperature of the filament f^1 , the latter through the transformer p^4, s^4 .

In Fig. 4 A is a thermionic or electronic device of the dynatron type wherein re-emission of electrons occurs from an electrode bombarded by a primary source of electrons. Within the evacuated vessel a there are the cathodes or filaments f and f^1 , grid g , electrode or anode v , electrode or grid g^1 and electrode or plate w .

The filament f^1 is connected in circuit, including switch d , transformer primary p^1 , microphone m and battery c . The transformer secondary s^1 is in the circuit of the grid g together with the device b and the transformer secondary s^5 , whose primary p^5 and the primary p^6 are connected in circuit with the source S of fluctuating or alternating current of any suitable frequency, as above audibility. There is a second grid circuit, that of grid g^1 , comprising the electrode or plate w , the transformer secondary s^7 and the transformer secondary s^8 , the former in inductive relation with primary p^1 and the latter in inductive relation with the primary p^6 .

The electrode or anode is in a circuit including the filaments f and f^1 , a variable portion of the battery B and the transformer primary p , with which is associated the secondary s . The electrode or plate w is also in a circuit including the primary p^8 , in inductive relation with the secondary s , and a variable portion of the battery B and the filaments f and f^1 .

With the switch d closed and switches e and h open, the number of electrons emitted by cathodes f and f^1 is varied by the microphone m which varies the temperature, as hereinbefore described, of the filament f^1 , which is made delicate or small for purposes of telephony or other high rate of variation. The grid g simultaneously varies the number of electrons from the cathode structure impinging upon the electrode or plate w , whereby the current through the primary p^8 is varied in accordance with speech. And simultaneously the number of electrons re-emitted by the electrode or

plate w and passing to the anode or electrode v is varied by the variations of potential of the grid g^1 , which may be so located or disposed between the elements w and v as to control only the electrons passing from electrode w to electrode v . Or as indicated in Fig. 4^a the grid g^1 may also be in the path of the electrons from the cathode structure f and f^1 , and also control electrons from that cathode structure passing to the electrode or plate w . The effect of control of the grid g^1 is therefore in the first case to modulate the current in the primary p including the anode or electrode v as due to the electrons from electrode w to electrode v . Secondly, it is, if properly disposed or positioned, to control electrons from f , f^1 to the electrode or plate w , to vary the current in the primary p^8 , or g^1 20 may perform both functions simultaneously. Furthermore, some of the electrons emitted by f , f^1 strike the electrode or anode v , and this direct action between f , f^1 and v is controlled by grid g , and so both affects the 25 current in the primary p as well as the current in the primary p^8 .

Accordingly current modulated in accordance with speech appears in the transformer secondary s , being induced therein by both 30 primaries p and p^8 .

If now the switch h be closed, the source S may pass through the primaries p^5 and p^6 oscillations or current of frequency above audibility which are impressed upon the 35 grids g and g^1 and controlled by the microphone m .

Or the filament f^1 may be cut out of circuit by opening the switch d and closing the switch e , whereupon the grids g and g^1 will 40 be controlled by the microphone m , and this is true whether or not the switch h is open or closed. When closed, of course, there will appear the high frequency modulations of grid potential modulated in turn by the 45 microphone m .

It will be understood as to all of the figures of the drawing that instead of delivering directly into the transmission circuit or into the radiating antenna or structure, the 50 secondaries s may deliver into intermediate audion or similar amplifying devices of any suitable number and power for producing any suitable amplification.

What I claim is:

55 1. An electronic device comprising an anode, a plurality of electron-emitting bodies connected to each other in the same anode circuit, and means for varying the electron emission of less than all of said bodies independently of the remainder to thereby vary the joint electron emission of said bodies to said anode.

2. An electronic device comprising an anode, a plurality of electron-emitting 60 bodies connected to each other, an electrode

between said bodies and said anode, and means for simultaneously varying the electron emission from less than all of said bodies and the potential of said electrode.

3. An electronic device comprising an anode, a plurality of electron-emitting bodies at substantially the same potential with respect to said anode, and means for varying in accordance with sound waves the number of electrons emitted by less than 70 all of said bodies to thereby vary the joint electron emission of said bodies to said anode.

4. An electronic device comprising an anode, a plurality of electron-emitting bodies connected to each other, an electrode between said bodies and said anode, and means for simultaneously varying in accordance with sound waves the electron emission from less than all of said bodies 85 and the potential of said electrode.

5. The combination with an electronic device comprising an anode and a plurality of electron-emitting bodies connected to each other, of means for causing in the circuit of 90 said anode a current varying at a frequency above audibility, and means for varying in accordance with sound waves the number of electrons emitted by less than all of said bodies.

6. The combination with an electronic device comprising an anode, a plurality of electron-emitting bodies connected to each other, and an electrode between said bodies and said anode, of means for causing in 95 the circuit of said anode a current varying at a frequency above audibility, and means for simultaneously varying in accordance with sound waves the potential of said electrode and the number of electrons emitted 100 from less than all of said bodies.

7. An electronic device comprising an anode, a plurality of cathodes connected to each other, means for passing current there-through to heat the same, and a signaling 110 instrument controlling the current in less than all of said cathodes.

8. An electronic device comprising an anode, a plurality of cathodes connected to each other, means for passing current there-through to heat the same, and means for varying in accordance with sound waves the current in less than all of said cathodes.

9. An electronic device comprising an anode, a plurality of cathodes connected to 120 each other, means for passing current there-through to heat the same, an electrode between said cathodes and said anode, and means for simultaneously varying the potential of said electrode and the strength 125 of the current through less than all of said cathodes.

10. An electronic device comprising an anode, a plurality of cathodes connected to each other, means for passing current there- 130

through to heat the same, an electrode between said cathodes and said anode, and means for simultaneously varying in accordance with sound waves the potential of 5 said electrode and the strength of the current through less than all of said cathodes.

11. An electronic device comprising an anode, a plurality of cathodes connected to each other, means for passing current there- 10 through to heat the same, an electrode between said cathodes and said anode, means for varying the potential of said electrode at a frequency above audibility, and means for simultaneously varying in accordance 15 with sound waves the potential of said electrode and the strength of current through less than all of said cathodes.

12. An electronic device comprising an anode, a plurality of cathodes connected to each other in the same anode circuit, means 20 for heating said cathodes, and means for controlling the temperature of less than all said cathodes independently of the remainder to vary their total electron emission.

25 13. An electronic device comprising an anode, a grid, a plurality of cathodes, means for heating said cathodes, and means for simultaneously controlling the temperature of less than all of said cathodes and the po- 30 tential of said grid.

14. Telephonic transmitting apparatus comprising an electronic device comprising an anode, a grid, a plurality of cathodes, and means including a telephone instrument for simultaneously varying the temperature of 35 less than all said cathodes and the potential of said grid.

15. An electronic device comprising an anode, a plurality of electron-emitting bodies 40 connected to each other in the same anode circuit, an electrode bombarded by electrons from said bodies and reëmitting electrons to said anode, and means for varying the electron output of less than all of 45 said bodies.

16. An electronic device comprising an anode, a plurality of electron-emitting bodies at substantially the same potential, an electrode bombarded by electrons from said 50 bodies and reëmitting electrons to said anode, and means for varying in accordance with sound waves the electron emission of less than all of said bodies.

17. An electronic device comprising an anode, a hot cathode, an electrode bombarded 55 by electrons from said body and reëmitting electrons to said anode, a second electrode between said electrode and said anode, and a signaling instrument simultaneously varying the potential of said second electrode and the temperature of said cathode.

18. An electronic device comprising an anode, an electron-emitting body, an electrode bombarded by electrons from said 60 body and reëmitting electrons to said anode,

a second electrode between said electrode and said anode, and means for simultaneously varying in accordance with sound waves the number of electrons emitted by said body and the potential of said second electrode. 70

19. An electronic device comprising an electron-emitting body, an anode, an electrode bombarded by electrons from said body and reëmitting electrons to said anode, and output circuits including respectively 75 said body with said anode and said anode with said electrode.

20. An electronic device comprising an electron-emitting body, an anode, an electrode bombarded by electrons from said body and reëmitting electrons to said anode, an output circuit including said body and 80 said anode, a grid between said electrode and said anode, and a source of alternating current varying the potential of said grid. 85

21. An electronic device comprising an electron-emitting body, an anode, an electrode bombarded by electrons from said body and reëmitting electrons to said anode, grids positioned, respectively, between said body and said anode and said anode and said electrode, and a source of alternating current simultaneously varying the potentials of said grids. 90

22. An electronic device comprising an 95 electron-emitting body, an anode, an electrode bombarded by electrons from said body and reëmitting electrons to said anode, and input circuits controlling the electron flow from said body to said electrode and 100 from said electrode to said anode.

23. An electronic device comprising an electron-emitting body, an anode, an electrode bombarded by electrons from said body and reëmitting electrons to said anode, input 105 circuits controlling simultaneously the flow of electrons from said body to said electrode and from said electrode to said anode, and an inductive coupling between said input circuits. 110

24. An electronic device comprising an electron-emitting body, an anode, an electrode bombarded by electrons from said body and reëmitting electrons to said anode, output circuits associated with said anode and said electrode, and input circuits controlling the flow of electrons from said body to said electrode and from said electrode to said anode. 115

25. An electronic device comprising an 120 electron-emitting body, an anode, an electrode bombarded by electrons from said body and reëmitting electrons to said anode, output circuits associated with said anode and said electrode, and input circuits controlling 125 the flow of electrons from said body to said anode and said electrode and from said electrode to said anode.

26. The method of controlling electrical energy in a circuit including a space trav- 130

ersed by electrons from a plurality of sources at substantially the same potential, which consists in recurrently varying the output of electrons from less than all of said sources 5 independently of the remainder to thereby vary from a predetermined normal total the electrons jointly emitted by said sources.

27. The method of controlling electrical energy in a circuit including a space traversed by electrons from a plurality of sources at substantially the same potential, which consists in controlling in accordance with a signal or message the electrons emitted from less than all of said sources independently of 10 the remainder to thereby vary from a predetermined normal total the electrons jointly emitted by said sources.

28. The method of controlling electrical energy in a circuit comprising a space traversed by electrons, which consists in causing reëmission of electrons by bombardment by electrons emitted by a plurality of sources at substantially the same potential, and recurrently varying the electrons emitted by 20 less than all of said sources independently of the remainder to thereby vary from a predetermined normal total the number of bombarding electrons.

29. The method of controlling electrical energy in a circuit including a space traversed by electrons from a plurality of sources, which consists in simultaneously varying the potential of an electrode in the electron stream from said sources and the 35 output of electrons from less than all of said sources to thereby vary from a predetermined normal total the electrons jointly emitted by said sources.

30. The method of controlling electrical energy in a circuit including a space traversed by electrons, which consists in causing reëmission of electrons by bombardment by electrons emitted by a plurality of sources, and simultaneously varying the potential of an electrode in the electron stream 40 from said sources and the number of elec-

trons emitted by less than all of said sources to thereby vary from a predetermined normal total the number of bombarding electrons.

31. The method of controlling electrical energy in a circuit including a space traversed by electrons, which consists in causing reëmission of electrons by bombardment by electrons emitted by an electron-emitting body, and simultaneously varying the potential of an electrode in the stream of re-emitted electrons and the electron emission from said body. 50

32. An electronic device comprising an electron-emitting body, an anode, an electrode bombarded by electrons from said body and reëmitting electrons to said anode, an output circuit including said body and said anode, a grid between said electrode and 55 said anode, and a plurality of different means simultaneously varying the potential of said grid. 60

33. An electronic device comprising an electron-emitting body, an anode, an electrode bombarded by electrons from said body and reëmitting electrons to said anode, grids positioned, respectively, between said body and said anode and said anode and said electrode, and a plurality of different means 65 simultaneously varying the potentials of said grids. 70

34. An electronic device comprising an electron-emitting body, an anode, an electrode bombarded by electrons from said body and reëmitting electrons to said anode, input 80 circuits controlling simultaneously the flow of electrons from said body to said electrode and from said electrode to said anode, an inductive coupling between said input circuits, 65 and a source of fluctuating current in said coupling. 75

In testimony whereof I have hereunto affixed my signature this 13th day of November, 1918.

CORNELIUS D. EHRET.
